UNITED STATES PATENT OFFICE

JEROME P. BYRON, OF LYNN, MASSACHUSETTS, ASSIGNOR, BY MESNE ASSIGNMENTS, TO EXCEL TAPING MACHINE CO., OF LYNN, MASSACHUSETTS, A CORPORATION OF MASSACHUSETTS

TAPE-APPLYING MACHINE

Application filed August 31, 1927. Serial No. 216,702.

This invention relates to a machine for applying adhesive reinforcing tape to sheets of material, such as the uppers of shoes.

Heretofore it has been usual to apply adhesive tape of this character to portions of shoe uppers or the like by means of a machine having an intermittently movable presser foot. Such a machine has tended to cause puckering or uneven application of the tape due to the lack of uniform conditions of pressure and tape speed and tension. This type of machine has been particularly unsuited to the application of tape to curved marginal portions of the vamp or to seams or the like.

The machine disclosed by the present invention may be used in applying a wide variety of tapes to base sheets such as shoe uppers, but it is particularly adapted to be used in conjunction with permanently adhesive tape which is coated with a plastic agglutinant that remains tacky indefinitely under ordinary temperature and humidity conditions. This tape is provided in rolls in which each tape layer is held rather tenaciously to the adjoining inner layer by the permanently tacky agglutinant. Thus it is necessary to use considerable force in pulling the tape from the roll. This characteristic has interfered seriously with the satisfactory working of tape applying machines previously used. The present invention is designed to obviate these difficulties by providing means for drawing the tape from the roll, and yet feeding the tape to the sheet independently of the effect of the tape tension required to draw it from the tape roll.

The present invention utilizes a continuously movable pressure roll which is held in yieldable engagement with the reinforcing tape and the sheet in order to press the tape into adhesive engagement with the sheet under uniform conditions of pressure and speed, while the adhesive character of the tape may be utilized for holding it taut to provide a constant tension so that the tape may be evenly fed and continuously applied to the desired portion of the sheet without puckering or wrinkling, although the elements of the machine are so arranged that the tension upon

the tape as it is drawn from the roll is not transmitted to the portion of the tape which is being fed into juxtaposition to the base sheet. In order to permit the easy and accurate application of tape to the upper, guide elements are arranged to engage and direct the movement of the tape and the sheet material, respectively, the guide element for the former being adjustable in order to receive tapes of different sizes and the guide element for the latter being adapted to engage the margin of the sheet although permitting the passage of projecting portions thereof, such as straps.

One important aspect of the invention relates to the arrangement of component elements of the machine, including the driving mechanism, the control mechanism and the means for permitting the insertion and removal of material, so that application of the tape may be made in the most rapid and convenient manner by the operator of the machine, thereby reducing fatigue and facilitating production. A further aspect of the invention concerns the provision of means for applying reinforcing tape to an upstanding rib, such as is formed by a seam between two sheet portions, for example, the conventional back seam of the ordinary shoe upper.

The above and further objects and advantageous features of the invention will be apparent to those skilled in the art upon a reading of the subjoined description and claims in conjunction with the accompanying drawings, in which:

Fig. 1 is a front elevational view of a portion of the improved tape applying machine;

Fig. 2 is a section on line 2—2 of Fig. 1;

Fig. 3 is a section on line 3—3 of Fig. 1;

Fig. 4 is a rear elevational view of the same;

Fig. 5 is an end view of a portion of the machine;

Fig. 6 is a section on line 6—6 of Fig. 1;

Fig. 7 is a detail view partly in elevation and partly in section showing the roller construction used for applying reinforcing tape to seams or the like; and

Fig. 8 is a sectional view of one form of tape guide taken on line 8—8 of Fig. 6.

A machine of the type exemplified in the accompanying drawings preferably comprises a frame, designated in general by the numeral 1 which may be mounted upon a suitable table or bench 22. One end of frame 1 preferably supports a train of gears designated generally by the numeral 2. This gear train is driven from any suitable source of power, such as an electric motor, by a belt 3 passing over a pulley 4. The latter is provided with a weighted rim 5 which not only comprises a flywheel, but also forms a hand wheel to permit manual movement of the gear train in order to permit accurate adjustment of the machine for the insertion of new work or for any other desired purpose. Mounted upon frame 1 is the transverse shaft 7 which is rotated by the gear 8 forming one of the elements of the train 2. Supported upon the opposite overhanging end portion of the shaft 7 is a roll 10 for receiving and feeding adhesive tape.

The upper roll support 12 is pivotally mounted upon the frame 1. This support 25 comprises a laterally extending member enclosing and supporting a rotatable shaft 13 and has a depending extension 14 which is provided with a pivot 16 engaging an upstanding portion 17 of frame 1 adjoining gear train 2. The intermediate portion of roll support 12 is provided with the depending flanges 15 which are adapted to engage the upstanding box-like guide member 18 upon frame 1; thus the member 12 may pivot 30 in a vertical plane, but is substantially prevented from horizontal movement in relation to frame member 1. Shaft 13 is provided with a gear 19 in loosely meshed engagement with gear 8 upon shaft 7, the arrangement of these gears permitting the limited 35 swinging movement of member 12 in relation to the remainder of the machine, as indicated by the dash lines of Fig. 4. The overhanging end of shaft 13 carries a press 40 roll 20 located above the roll 10 and preferably somewhat narrower in width and smaller in diameter than the same (Figs. 4 and 5).

One of the depending flanges 15 upon 50 member 13 is secured to a rod 21. The latter carries a collar 23 and an adjusting nut 26 screwed upon its end. The lower end of spring 25 is engaged by this adjusting nut while its upper end is engaged by a lug 29 55 that projects from frame 1 and has an opening to permit movement of rod 22 therethrough. Interposed between collar 23 and lug 29 is the end of rocker arm 30, the mid portion of which is pivotally mounted on 60 stud 31 that projects from frame 1, and the end portion of which engages a control link 32 that extends downwardly to any suitable treadle or controlling element (not shown). Thus spring 25 normally urges nut 26 and 65 rod 21 downwardly thus cooperating with

the weight of support 12 and the related parts in tending yieldably to hold rollers 10 and 20 in juxtaposition. Rock arm 30 and link 32 are arranged so that downward movement of the latter causes the member 12 to be swung upwardly to the dash line position of Fig. 4, due to the engagement of arm 30 against collar 23, the gears 8 and 19 limiting this movement.

Mounted upon frame 1 is a detachable bed plate or table 37 preferably disposed in a plane which is substantially tangent to both roll 10 and roll 20. An opening 38 in the intermediate portion of plate 37 permits the rolls to contact or to engage the tape and sheet material.

A suitable braid guide designated in general by numeral 40 is also adjustably mounted upon frame 1 (Figs. 2 and 6). This guide preferably is provided with a downwardly extending support portion 41 provided with slots 42 through which fastenings 43 extend to clamp the guide member in the desired adjusted position. As shown, the curvature of guide element 40 preferably is designed closely to parallel the periphery of the tape feed roll 10. The body portion of the guide member comprises a curved metal strip 44 provided with a rabbet 45 adapted to receive the reinforcing tape. Adjustably mounted upon member 44 is the plate 46 having a depending flange 47, the arrangement of the plate and the flange cooperating with rabbet 45 to provide a curved passage to direct the tape into proper relation to the substantially superimposed rolls 10 and 20. Adjustment of member 46 laterally, as permitted by screws 49 and slots 50, permits variation in the width of the tape receiving portion of member 40.

Adjoining the juxtaposed portions of rolls 10 and 20 is a yieldably mounted sheet retaining element 60 carrying a small roller 65 with its axis parallel to the axes of rolls 10 and 20. Preferably this element is supported from a laterally adjustable bracket 61 which is secured to member 12. The retaining means is provided with a spring 62 which tends to press roller 65 downwardly into engagement with the portion of roll 10 which extends inwardly beyond roll 20, due to the greater width of the former.

Located adjoining rolls 10 and 20 is the shaft 70 upon which is mounted during operation of the machine a roll of adhesively coated tape, designated by numeral 71. Preferably this tape is coated with a permanently plastic adhesive which remains tacky for an indefinite period under ordinary conditions of temperature and moisture. The axis of this roll preferably is parallel to the axis of roll 10 and is arranged substantially on a level with the lowermost portion of that roll so that a run 80 of tape extends from the adhesively coated roll in a direction that 130

intersects that roll and is substantially tangential to roll 10 at its lowermost point. If desired a rod 81 may be located adjoining roll 71 to aid in defining the position of the tape run 80, although it is feasible to depend upon the adhesive engagement of the outer layer of tape with the adjoining tape layer for this purpose. The adhesively coated tape is then wrapped around a portion of roll 10 which preferably has its surface roughened by fine knurling or the like, designated by numeral 73; the tape then extends through the tape guide 40 which serves accurately to position the tape in a lateral direction, thence the tape is directed upwardly through opening 38 to a position above plate 37. Sheet material, such as the upper of a shoe to which the reinforcing tape is to be applied, is fed above plate 37, and if the tape is to be applied to the margin of the sheet material, this margin is held against the retaining roll 65, thus the tape and sheet member are accurately held in alignment and the yieldable engagement of rolls 10 and 20 serves to press the tape into firm adhesive engagement with the shoe upper or the like.

The use of a smaller and narrower upper roll permits the convenient movement or manipulation of the sheet member so that the tape may be applied to the curved edge of a member of this character, the smaller area of contact resulting from this arrangement permitting the easier turning of the sheet. The yieldable mounting of roller 65 permits its upward movement so that projecting straps and the like may pass by the retaining member without interference with the normal operation of the machine.

In the operation of a machine of this character, downward movement of link 32, due to the action of the foot of the operator or the like, serves to raise roller 20 out of engagement with roller 10, so that a sheet member such as a vamp, or shoe upper may be interposed between the rolls. Meantime the

uniform tension as it is wrapped around the knurled portion of the lower roll 10. The frictional engagement of the tape with the roughened periphery of this roll serves to draw it from the tape roll 71, thus overcoming the tenacious adhesive engagement of the outer tape layer with the adjoining tape layer. The feeding of the tape from the periphery of roll 10 through guide member 40 to the point where it is again engaged by the portion of roll 10 which is closest to roll 20 results in the application of the tape to the base sheet while it is substantially free from tension, so that the tape and sheet are brought together, under similar uniform conditions.

When tape has thus been applied to the desired portion of the sheet, the machine may be stopped, the rolls 10 and 20 separated, and the tape cut so that the succeeding sheet may then be inserted in the machine and the operation repeated by engaging the succeeding sheet with the end portion of the tape between the rolls and again starting the machine.

While this invention is particularly applicable to use in conjunction with adhesive tape of the type having a permanently tacky agglutinant, it is also adaptable for use with tape of other types, for example tape having an adhesive coating which requires heating before it is applied to the base sheet or the shoe upper. For this purpose, it may be desirable to provide the cover 46 of guide member 40 with a heating element such as an electrical resistance factor 90 in order to soften the agglutinant and to render the same properly adhesive for application to the base sheet (Fig. 8). A machine having a heating element of this type may thus be used with either tape having a permanently tacky coating or with tape which requires heating before it can be adhesively united with the base sheet.

Fig. 7 shows a form of the invention which

rious forms of rolls are readily interchangeable to suit the particular work in hand and that rolls 110, 120 are as desirable and useful in combination with the rest of the machine as the plain rolls illustrated therewith.

5 When rolls 120 and 110 are used, the yieldable mounting of retaining member 65 will permit it to ride over the surface of the interposed sheet, as shown in Fig. 7, while the table 37 may be removed if desired.

10 It is evident that I have provided a machine adapted to feed and apply adhesive reinforcing tape accurately and evenly to any desired portion of a sheet, whether a straight or curved margin, or an intermediate seam.

15 While this machine is particularly suited to the application of reinforcing material to shoe uppers, I am using the term "sheet" in the foregoing specification and in the following claims in order to indicate any suitable leather fabric or the like to which reinforcing tape of this character might be advantageously applied.

I claim:

20 1. In a machine of the class described, a pair of substantially superimposed rolls, said rolls being yieldably urged toward each other, the lower roll having a roughened surface more firmly to engage tape, means for 25 rotating the rolls, and guide means arranged to receive a tape run wrapped about the lower roll and to feed tape substantially free of 30 tension between the rolls and to permit the movement of a sheet between the same, 35 whereby the tape and sheet may be pressed together between the rolls and may be moved at the same speed.

25 2. In a machine of the class described, a pair of juxtaposed rolls, means yieldably urging the rolls toward each other, means for 30 rotating the rolls and guide means arranged to feed tape between the rolls and to permit the movement of a sheet between the same, said guide means comprising a curved member shaped to receive the tape and to guide it along a curved path substantially parallel to the curvature of one of said rolls, and a heating factor in said member.

35 3. In a machine of the class described, a pair of juxtaposed rolls, said rolls being yieldably urged toward each other, means for 40 rotating the rolls, and guide means arranged to feed tape between the rolls and to permit the movement of a sheet between the same, said guide means comprising a curved member shaped to receive the tape and to guide it along a curved path substantially parallel to the curvature of one of said rolls, the tape receiving portion of the curved guide 45 member being adjustable in width.

40 4. In a machine of the class described, a pair of juxtaposed rolls, means yieldably urging the rolls toward each other, means for 45 rotating the rolls, and means adjacent the juxtaposed portions of the rolls for prevent-

ing the sheet from moving in a direction parallel to the axes of the rolls, said means comprising a yieldably retained member adapted normally to engage a margin of the sheet but yieldably to move to permit the passing 50 of projections upon the sheet.

5. In a machine of the class described, a pair of juxtaposed rolls, said rolls being yieldably urged toward each other, means for 55 rotating the rolls, and guide means arranged to feed tape into the space between the rolls and to permit the movement of a sheet between the same, and means adjacent the juxtaposed portions of the rolls for preventing work from moving in a direction 60 parallel to the axes of the rolls, said means comprising a yieldably retained roller designed normally to engage a margin of the sheet but yieldably to move to permit the passing of projections upon the sheet, said roller having its axis arranged substantially 65 parallel to the axes of the juxtaposed rolls.

6. In a machine of the class described, a pair of juxtaposed rolls, means yieldably urging the rolls toward each other, means for 70 rotating the rolls, and guide means arranged to feed tape between the rolls and to permit the movement of a sheet between the same, and a detachably mounted, flat supporting surface with an opening to receive 75 the adjoining portions of the juxtaposed rolls, whereby the tape and sheet may be pressed together between the rolls and be moved at the same speed.

7. In machine of the class described, a pair 80 of juxtaposed rolls, means yieldably urging the rolls toward each other, one of said rolls having a peripheral rib, the other roll having a complementary peripheral groove whereby tape may be pressed upon an 85 standing seam, and guide means arranged to feed tape between the rolls and to permit the movement of a sheet between the same whereby the tape and sheet may be gripped between the rolls to be moved at the same speed.

8. In a machine of the class described, a pair of juxtaposed rolls, said rolls being yieldably urged toward each other, meshed gears for driving the gears, guide means arranged to feed tape into the space between the rolls and to permit the movement of a sheet between the same, and control means operable by the operator of the machine for moving the juxtaposed rolls apart to permit the insertion or removal of work, said means comprising a swinging member upon which one of the rolls is mounted, said meshed gears being normally arranged in loose engagement to permit the rolls to move apart and to limit said movement.

9. In a machine of the class described, a pair of juxtaposed rolls, a tape support positioned to supply a run of tape to a peripheral portion of one of said rolls that is remote from the bite of the rolls, means to receive the 130

tape from said peripheral portion of the roll and to hold the tape run out of contact with a peripheral portion of that roll between the first-named portion and the portion which is 5 juxtaposed to the other roll, whereby tape may be fed between the rolls substantially free from tension.

10. In a machine of the class described, a pair of juxtaposed rolls, means yieldably urging the rolls toward each other, means for rotating the rolls, a support for a roll of tape which has an adhesively coated surface upon the inner face of each of its layers binding it to the outer face of the adjoining layer, said 15 support being positioned in relation to one of the juxtaposed rolls to supply a run from the tape roll to the peripheral portion of that roll, said peripheral portion being remote from the bite of the aforesaid rolls, a guide 20 member adjoining the bite of the rolls and arranged to receive the tape run from the aforesaid peripheral portion and to hold the same out of contact with the rolls as it passes to the bite thereof, whereby the tape and a 25 sheet may be gripped between the rolls and be moved at the same speed without the adhesive engagement of the layers of tape in the tape roll imposing excessive tension upon the tape as it is applied to the sheet.

30. 11. A machine of the class described comprising a pair of juxtaposed rolls, means yieldably urging the rolls toward each other, means for rotating the rolls, a support for a roll of tape having its concentric layers held 35 in adhesive engagement with each other, said support being arranged to position the axis of the tape roll at one side of a plane containing the axes of the juxtaposed rolls and arranged to supply a run of the tape to a 40 peripheral portion of one of the rolls which is remote from the bite of the same and a guide member adjoining the bite of the rolls arranged to receive the tape run from said peripheral portion before it passes into the 45 bite of the rolls.

12. A machine of the class described comprising a pair of juxtaposed rolls, means yieldably urging the rolls toward each other, means for rotating the rolls, a support for a 50 roll of adhesively coated tape, an idler member positioned to receive a run of tape from a roll of the same that is mounted upon the support, said support and idler member being so disposed in relation to the juxtaposed 55 rolls as to direct the tape run into frictional engagement with a considerable peripheral portion of one of the rolls, this peripheral portion being remote from the bite of the rolls.

60. 13. A machine of the class described comprising a pair of juxtaposed rolls, means yieldably urging the rolls toward each other, means for rotating the rolls, a support for a roll of adhesively coated tape, an idler member positioned to receive a run of tape from a 65

roll of the same that is mounted upon the support, said support and idler member being so disposed in relation to the juxtaposed rolls as to supply the tape run into frictional engagement with a considerable peripheral portion of one of the rolls which portion is remote from the bite of the rolls, and a guide member to receive the tape run from the peripheral portion of the roll, whereby the tape is guided out of contact with the roll as it passes from the aforesaid peripheral portion to the bite of the rolls.

Signed by me at Lynn, Mass., this 19th day of Aug., 1927.
